Attorney

UNITED STATES PATENT OFFICE.

JULIUS ROSENZWEIG, OF NEW YORK, N. Y.

ADJUSTABLE CAP.

Application filed November 26, 1923. Serial No. 677,053.

To all whom it may concern:

Be it known that I, JULIUS ROSENZWEIG, citizen of the United States, residing at New York, State of New York, have invented 5 certain new and useful Improvements in Adjustable Caps, of which the following is a specification.

This invention relates to certain new and useful improvements in adjustable caps 10 made of cloth or similar material and it has for its objects among others to provide an improved cap of that general type having provision for ready adjustment so that the one cap can be made to accommodate itself 15 with equal facility when caps of different sizes are required, thereby enabling a dealer in caps to carry a less number of caps and yet be able to accommodate his customers with the required size of cap.

20 My improved cap embodies a skirt portion upon each side of the front center with ends separated and provided with rows of holes which are preferably in a reinforcing member on the under side of each skirt portion, and a member traversing the space between the said reinforcing members and having at each end a hook engageable in said holes, the ends of the strap being secured to opposite edges of the peak or visor.

25 Other objects and advantages of the invention will hereinafter appear, and the novel features thereof will be particularly pointed out in the appended claim.

The invention is clearly illustrated in the 30 accompanying drawings, which with the numerals of reference marked thereon, form a part of this specification, and in which

Figure 1 is a perspective view of a cap embodying my present invention.

40 Figure 2 is a section as on the line 2, 2 of Fig. 1 looking in the direction of the arrows.

Referring to the drawings:

45 1 designates the crown of the cap, 2 the peak or visor, and 3 and 4 the female and male portions of a separable or snap fastener, of usual type, so disposed that when the front of the crown is drawn down and the fastener members engaged the size-adjusting elements, now to be described, will be concealed from view.

At the front of the crown are the skirt portions 5 and 6, that at the right of Fig. 1 being shown as thrown upward for the purpose of illustration. As seen best in Fig. 2 the adjacent ends of these skirt portions are separated, and to the inner face of each thereof there is secured a reinforcing member 7, 8 as seen in Fig. 2, which may be leather or other suitable material provided with a plurality of holes 9, which may be reinforced if desired by means such as eyelets or the like 10 as seen in Fig. 1.

The underside of each of the members 7 and 8 is preferably provided with a loop 11 through which is guided the ends of a strap 12, preferably of the same material as the cap. This strap 12 after having its ends passed through the loops 11 has such ends fastened to the opposite edges of the visor as by rivets or the like 13, see Fig. 2, which rivets also secure in place at the ends of a strap the members 14 of the pivoted hooks 15 which are adapted to engage in the holes 9 of the members 7 and 8.

The size of the cap may be readily adjusted by moving the skirt portions in either direction, toward or from each other, and then engaging the hooks in the holes 9. The skirt portions at all times cover and conceal the adjusting means.

Modifications in detail may be resorted to without departing from the spirit of the invention or sacrificing any of its advantages.

85 What I claim as new is:

A cap having a crown, a visor and separated skirt portions independent of the sweat band, reinforcing members secured to the skirt portions and having a series of holes, loops on the underside of said skirt portions, a strap guided at its ends in said loops with its ends fastened to opposite edges of the visor, and pivoted hooks on the ends of said strap and engageable in the holes of said reinforcing members.

In testimony whereof I hereunto affix my signature.

JULIUS ROSENZWEIG.

Witnesses:

JOSEPH FERMAN,
IRVING STEIN.
